UNITED STATES PATENT OFFICE.

OLIVER M. BABCOCK, OF CHICAGO, ILLINOIS, ASSIGNOR, BY MESNE ASSIGNMENTS, TO WIREBOUNDS PATENTS COMPANY, OF KITTERY, MAINE, A CORPORATION OF MAINE.

METAL-BOUND BOX.

1,334,068.

Specification of Letters Patent. Patented Mar. 16, 1920.

Application filed March 27, 1914. Serial No. 827,565.

To all whom it may concern:

Be it known that I, OLIVER M. BABCOCK, a citizen of the United States of America, and resident of Chicago, Cook county, Illinois, have invented a certain new and useful Improvement in Metal-Bound Boxes, of which the following is a specification.

This invention is intended to provide certain improvements in metal bound boxes, and the method of their construction, and to provide an improved box adapted for packaging material such as tea, sugar, or fabrics, clothes and other articles and materials.

The invention will be more clearly understood by reference to an illustrative embodiment thereof shown in the accompanying drawings, in which:

Figure 1 is a perspective view of the illustrative box.

Fig. 2 is a detail of a box and binding strip fastening.

The illustrative box comprises four side sections composed of side material and cleats connected together in foldable relationship by flexible metal strips, the sheets, cleats and strips being so assembled that the cleat ends mutually engage and the side sheets meet with overlapping edges.

As usual in such constructions the side sheets, as well as the ends or top and bottom, may be composed of light and cheap material such as thin lumber, veneer, cardboard or the like, the material being reinforced on one side by the cleats and on the other side by the binding material.

The side-forming sheets may be assembled in sets such as E, E¹, E² and F, F¹, F², which are held together by the wires, metal bands G or other flexible binding members herein-after referred to as binding strips. The side-forming sheets, binding means and cleats A⁸ are preferably assembled in correct relationship and secured together in a box blank machine of known type wherein the assembled materials are fed under a gang of stapling mechanism, the binding strips being laid upon the materials, and the whole secured together to form a foldable box blank. The cleats A⁸ are shown inset in the head of the box, although they may be otherwise arranged such as flush with the top or arranged on the outside or inside or both.

The ends may each be formed in one or

more pieces and may be rigidly secured to the box by means of other metal strips G¹ which, as shown in the illustration, are disposed at right angles relatively to the strips G. These strips G¹ may, if preferred, completely encircle the box.

In all cases the strips may be secured to the box blanks or ends and the ends of the strips themselves may be joined or fastened in place by means of staples, nails or the like passing completely through the metal or straddling the same and also preferably passing completely through the box blank material; they may be fastened by other suitable means as found desirable in any particular case.

The strips G and G¹ are preferably applied in a heated condition so as to obtain benefit of the tightening or binding action which will occur when they cool. The invention, however, is not limited to the application of the strips in a heated condition, as they might be quite conveniently applied in a cold state.

The strips G¹ according to one construction are secured by their ends G² to the sides of the box by holding means such as nails, staples, or the like, and are so disposed that the holding means engage the cleats A⁸ after passing through the strips and the box sides E, E¹, E².

In a construction shown in Fig. 2, holes, preferably two in number and side by side, may be drilled through the metal strips and the side of the box so that by passing a continuous length of wire or other connector through the holes (for example in through one and out through the other) and securing it by twisting its ends or otherwise, the strip ends or the box end may be secured in place.

To enable the box to be more readily adapted for sugar, tea or other similar articles, it may be lined as at H with paper, lead foil or other flexible lining or if the box is to be used for heavy articles it may be lined with any suitable stout or thick material such as sackings. The same feature of applying a lining may be embodied in the case of crates constructed in accordance with this invention. The lining is preferably secured between the end-strengthening cleats and the side-forming sheets, and it may be stitched or stapled in and assembled together with the other parts of the box. In

stead of or in addition to the lining, an outer lining or covering for the box may be applied when the box parts are assembled.

It is preferable to form one end in two portions or sections J , J^1 , or even in more than two portions or sections. The portion J is preferably rigidly secured to the box sides or to the cleats A^8 when the box is assembled, by nails or staples or in any other 10 convenient manner, while the portion J^1 serves as a lid, the hinges of which are constituted by the strips G^1 secured to and connecting the portions J and J^1 . After the box has been filled with the material which 15 it is intended to accommodate, the lid portion J^1 may be secured to the box, as previously described. The portion J^1 may be used as a lid during packing or unpacking of the contents and the box may be used 20 many times over.

The end may be formed of more than two sections, for instance, the portion J might be interposed between two portions J^1 , in which event the box would be provided with two 25 openings instead of one. This construction might be useful if it were desired to divide the box into two parts by a partition to accommodate two different substances for shipment or storage.

30 It will be understood that the box blanks may be made by wiring the different side sections thereof together by successive stapling operations thereon, in any suitable known or approved manner, as by carrying 35 the blanks forward below a plurality of staplers. If a sheet of paper is to be applied to the box, to form a lining or inner wrapper therefor, the said sheet can be incorporated in the blank while the four sections thereof are being wired together by 40 the successive stapling operations. This can be done, for example, by feeding the paper from a roll to the advancing blank, and in such manner that the paper and the 45 blank materials advance in a step-by-step manner below the staplers, whereby the staples will fasten the wires and veneer and cleats and sheet of paper together. The paper can then be cut or severed at the rear 50 end of the blank, and the result is a flexible wire bound blank having a sheet of paper extending from one end thereof to the other, thereby providing a tight box when the box 55 is finished. The sheet of paper can be fed in between the cleats and the sheets of veneer, or between the veneer and the binding wires, depending upon the character of the paper and the particular use or purpose for which the box is to be employed. The 60 paper can be of a water-proof nature, if necessary, and any other suitable known or approved sheet material can be employed for this purpose.

What I claim as my invention is:—

65 1. A metal-bound box, substantially as

described, in which one of the ends is formed in a plurality of portions and binding means connecting them, certain of which portions may be rigidly secured in place while another portion may serve as a lid utilizing the 70 binding strips as hinges.

2. A box comprising sheets, cleats and binders having one side formed in a plurality of sections foldably connected by the binders, one of said sections being free to 75 be folded with respect to an adjacent box portion, whereby a reinforced box having a foldable lid is provided.

3. In a metal bound box, the combination of a binder having overlapping ends and a 80 fastener therefor comprising a wire loop encircling a portion of the box side contiguous to said binder, and having its legs passing through apertures in said overlapping ends and twisted together to tightly confine said 85 overlapping ends.

4. A metal bound box comprising relatively foldable sections for four sides of the box, having coöperating end cleats, and connected together by box encircling bindings; 90 the cleats at one end of the box being inset from the corresponding edges of the side sections; and a box head or end embraced by said side sections and applied to the outer faces of said inset cleats. 95

5. A metal bound box comprising relatively foldable sections for four sides of the box, having coöperating end cleats, and connected together by box encircling bindings; the cleats being inset from the corresponding edges of the side sections; and box heads or ends embraced by said side sections and applied to the outer faces of the cleats; a box head including a removable section and fastening means therefor. 100

6. A metal bound box comprising relatively foldable sections for four sides of the box, having coöperating end cleats, and connected together by box encircling bindings; the cleats being inset from the corresponding edges of the side sections; box heads or ends embraced by said side sections and applied to the outer faces of the cleats; and means separably fastening a box head to cleats. 105

7. A metal bound box comprising relatively foldable sections for four sides of the box, having coöperating end cleats, and connected together by box encircling bindings; the cleats being inset from the corresponding edges of the side sections; box heads or ends embraced by said side sections and applied to the outer faces of the cleats; and transverse reinforcing members secured to said head and to opposite side sections. 115

8. A box having four sides and a bottom, metallic binding members extending around the sides, in horizontal planes and connecting said sides in foldable relationship, binding members extending across the bottom, 120

- secured at their ends to the sides of the box, a cover for the top of the box, binding members extending across the cover, secured at their ends to the sides of the box, and 5 inset cleats at top and bottom of the box, extending around the inside thereof, forming seats for said bottom and cover, the bottom and cover being fitted within the sides.
9. A metal bound box having interior 10 cleats framing the top and inset from the edge thereof, a metallic binding encircling the mouth of the box and secured through the sides to said cleats, a cover resting on said cleats flush with the box top and means 15 for securing said cover.
10. An open-top box having interior 10 cleats framing the top and inset from the edge thereof, a binding encircling the mouth of the box and secured through the sides to 20 said cleats, a cover resting on said cleats, flush with the box top and means for securing said cover to said binding.
11. A box comprising side sections reinforced by lateral cleats mating to form box-supporting frames and connected by box- 25 encircling bindings and a closure therefor supported by the cleats and including a number of sections foldably connected by 30 bindings, a section being secured to said cleats and another being free to fold relatively thereto on said bindings.
12. A metal bound box comprising foldably related sections for four sides of the box having coöperating end cleats and connected together by box-encircling bindings; 35 and an outwardly displaceable end section embraced by said side sections and separably secured in place.

Signed by me at Chicago, Illinois, this 25th day of March, 1914.

OLIVER M. BABCOCK.
